UNITED STATES PATENT OFFICE.

JOSEPH SOSS, OF BROOKLYN, NEW YORK.

HINGE.

Application filed December 15, 1924. Serial No. 755,863.

This invention relates to hinges and particularly to what are known as covered joint hinges wherein the separate butts of the hinge are fashioned from sheet metal; and the object of the invention is to provide a hinge of the class specified, one of the butts of which is formed from a strip of sheet metal, one end portion of said strip being fashioned to form a hook-shaped end portion and a knuckle within the hook-shaped end portion whereby said knuckle forms the pivot portion of said butt and the hook-shaped portion thereof forming a hood for partially closing the pivot portion of the butt; a further object being to provide a hinge of the class described, one of the butts of which is fashioned from sheet metal and the end portion thereof being curved and fashioned to form a hood having top and bottom walls, and a pintle bearing within said hook-shaped end portion; a still further object of the invention being to materially simplify the construction of a hinge of the class under consideration whereby the manufacturing costs are reduced and a strong and durable hinge produced; and with these and other objects in view, the invention consists in a hinge of the class specified and in the improved method of producing the same hereafter more specifically set out in the specification and claims.

The invention is fully disclosed in the following specification, of which the accompanying drawing forms a part, in which the separate parts of my improvement are designated by suitable reference characters in each of the views, and in which:

Fig. 1 is a face view of a hinge made according to my invention with part of the construction broken away.

Fig. 2 is a plan view of a blank or a part of a blank from which one butt of the hinge is formed and indicating the first step in fashioning said blank.

Fig. 3 is a side edge view of the blank shown in Fig. 2 and illustrating the next step in the operation.

Fig. 4 is a view similar to Fig. 3 but showing another step.

Fig. 5 is a plan view of one end portion of a hinge butt diagrammatically illustrating the next step in the process of making the same.

Fig. 6 is a side edge view of the construc-

tion shown in Fig. 5 but showing the result of an additional trimming operation.

Fig. 7 is a longitudinal sectional view through the separate butts of the hinge with part of the construction broken away; and

Fig. 8 is a plan view of the pivot ends of the separate butts of a hinge showing a slight modification in the formation of one of the hinge butts.

My invention relates to the construction of what are known as covered joint hinges and particularly to the construction of hinges of this class of two sheet metal hinge butts, and more particularly to the construction of the hinge butt provided with the means for covering or partially covering the joint of the hinge.

In carrying my invention into effect, I provide a blank in the form of a strip or sheet of metal 10 of predetermined dimensions and in constructing the hinge from said blank, the corner portions at one end thereof are cut out as indicated in dot and dash lines at 11 in Fig. 2 of the drawing, leaving at said end portion a projecting tongue member 12 of less transverse dimensions than the remainder of said blank. The end portion of the blank including the tongue member 12 is then fashioned to form a curved end portion 13 and in this operation the tongue member 12 is brought into engagement with one face of the blank 10 and the shoulders 14 formed by the cut out corner portions 11 are arranged at an angle to the blank 10 as clearly seen in Fig. 3 of the drawing.

The next step in the formation of the hinge butt consists in arranging the curved end portion 13 into position to facilitate the fashioning of said end portion into predetermined formation, which result may be accomplished by the angular positioning of the blank thus formed as indicated in full and dotted lines in Fig. 4 of the drawing or by bending the blank in the manner shown in full lines only in said figure. By means of suitable dies, the curved end portion 13 as well as the tongue member 12 is fashioned to form thereof a curved hood portion 15 within which is a pintle bearing 16, the hinge being recessed at the opposite sides of the pintle bearing as shown at 17 to receive the knuckles or pintle bearings on the other part or butt of the hinge; the above result

being produced by dies which depress the shoulder portions 14 and curved end portion 13 of the blank when positioned substantially as shown in Fig. 4 to force the metal 5 into position to form comparatively thin walls 18 at the opposite sides of the bearing 16 which constitute part of the hood, said walls 18 gradually increasing in dimensions or thickness in extending into the plate of 10 the hinge butt as clearly illustrated at 19 in Fig. 6 of the drawing. It will be understood that in the above forming operation a shoulder 20 is formed upon the periphery of the bearing 16, and the surface of this 15 shoulder is in parallel relation to the free edges of the hood portion 15.

In the above operation of forming the hinge, a flare of the metal as diagrammatically illustrated at 21 will result and the 20 flares will be trimmed off in the next or trimming operation on the hinge.

The next step in forming the hinge consists in shaping and sizing the same which will include the rebending of the hinge from 25 the full line position shown in Fig. 4 back into the dotted line position, after which the small aperture 22 formed within the bearing 16 in its making, is bored or reamed to suit the size of a predetermined pintle pin 30 23. It will also be understood that in the above described operation of fashioning the side portion of the blank to form the recesses 17 at the opposite sides of the bearing 16 and in the general shaping of the said 35 end portion of the blank, a rough pin may be inserted into the aperture 22 to prevent the collapsing of the tongue 12 which partially forms the bearing 16.

It is also preferred that the knuckles 24 40 of the other member or body 25 of the hinge be fashioned to form shoulders 26 which will cooperate with the shoulder 20 to form a stop for limiting the swinging movement of one butt upon the other within predetermined degrees, it being understood however 45 that the shoulder 20 may strike upon the face of the butt 25 to serve as a stop, the shoulder 20 being positioned on the butt formed from the blank 10 to provide for a predetermined swing of the hinge butts.

It will be understood that with the construction shown in Figs. 1 to 7 inclusive, that the knuckles or bearing 24 of the hinge butt 25 are exposed through the top and bottom 55 faces of the hinge (note Fig. 1 of the drawing) the hood 15 extending around the knuckles 24 to partially close the same and to form a covered joint hinge. However, in Fig. 8 of the drawing I have shown a modification in which the top and bottom faces of the knuckles 28 are closed by walls 26 formed integral with the blank 10 or integral with the curved end portion of said blank and one of these walls is shown in said figure, and 60 65 these walls are apertured as shown at 27 to

receive the pintle pin 23, and the apertures 27 may open outwardly through the walls 26 as indicated at 28 which facilitates the cutting of the apertures 27 which are angular particularly in one of the walls 26 to receive the angular shank or portion of a pintle pin to prevent the rotation of said pin in the hinge butt formed from the blank 10. It will be understood however, that I am not necessarily limited to the specific formation 70 of the apertures 27 herein set out, nor am I limited to the specific shape or form of the curved end or hood portion of the hinge butt, and the pintle bearing within said hood portion, and various changes in and modifications of the construction herein shown and described and the method herein set out may be made within the scope of the appended claims without departing from the spirit of my invention or sacrificing its advantages. 75 80 85 90

It will be apparent that in the finish trimming, sizing and shaping of the hinge butt fashioned from the blank 10, the top and bottom faces of the pintle bearing 15 may be finished and brought to predetermined 95 spaced relation to receive the other butt of the hinge, and the recesses 17 cleaned out if necessary to provide the free action of the separate butt members one upon another.

Having fully described my invention, 95 what I claim as new and desire to secure by Letters Patent, is:—

1. A hinge butt fashioned from a sheet metal blank, the pivot end portion of which is curved or hook-shaped in form and provided centrally thereof with an enlarged stock or body forming the bearing for a pintle pin, and said curved end portion of the butt at the opposite sides of the enlarged stock or body being fashioned into comparatively thin walls gradually increasing in thickness as they extend into the plate of the butt and forming recesses at the opposite sides of the pintle bearing. 100 105

2. A hinge butt composed of sheet metal and provided at one end portion thereof with a curved hood portion and an integral pintle bearing portion partially formed by said hood portion, at the opposite sides of which and within the hood portion are recesses to receive the pintle bearings of the other butt of a hinge, and said hood portion including end wall members extending at right angles to the butt and of a shape substantially similar to the cross sectional form 110 115 120 of said pintle bearing portion.

3. A sheet metal hinge butt of the class described, the pivot end portion of which is curved or hook-shaped in form and provided centrally with an enlarged stock or body substantially cylindrical in form and forming the bearing for a pintle pin and the curved end portion of the butt at the opposite sides of the enlarged stock or body extending at right angles to form end wall 125 130

members corresponding substantially in form to the cross sectional form of said bearing, and forming between the same and said bearing recesses to receive the pintle bearings of the other butt of the hinge. 5

4. In a hinge, a pair of sheet metal hinge members fashioned to form at one end thereof interengaging knuckles, the knuckle end portion of one of said hinge members being 10 fashioned to form a hood portion having an integral pintle bearing centrally of and within the hood portion and partially formed by said hood portion, the hood portion of said hinge member extending at the top 15 and bottom edges thereof to form end walls adapted to enclose pintle bearing portions only of the other member of the hinge.

5. A hinge butt composed of sheet metal and provided at one end thereof with a 20 curved hood portion, a pintle bearing within said hood portion and partially formed thereby and by an extension on said hood portion, a shoulder on said pintle bearing

in line with the free edge of the hood portion and recesses at the opposite sides of said 25 pintle bearing adapted to receive the pintle bearings of the other butt of a hinge.

6. A hinge butt composed of sheet metal and provided at one end thereof with a curved hood portion, a pintle bearing within 30 said hood portion and partially formed thereby and by an extension on said hood portion, a shoulder on said pintle bearing in line with the free edge of the hood portion, recesses at the opposite sides of said 35 pintle bearing adapted to receive the pintle bearings of the other butt of a hinge, and said hood portion extending at the top and bottom edges thereof to form end walls 40 adapted to enclose the pintle bearing portions only of the hinge.

In testimony that I claim the foregoing as my invention I have signed my name this 5th day of Dec., 1924.

JOSEPH SOSS.
